DESIGN FOR A DRESS

Katheryn Rost, New York, N. Y.

Application January 23, 1947, Serial No. 136,341

Term of patent 3½ years

(Cl. D3—26)

To all whom it may concern:

Be it known that I, Katheryn Rost, a citizen of the United States of America, residing in New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

KATHERYN ROST.
